(57) **CLAIM**

The ornamental design for a crossbow case, as shown and described.

DESCRIPTION

FIG. 1 is a perspective view of a crossbow case in accordance with an embodiment of the present disclosure.

FIG. 2 is a top view of the crossbow case of FIG. 1.

FIG. 3 is a bottom view of the crossbow case of FIG. 1.

FIG. 4 is a side view of the crossbow case of FIG. 1.

FIG. 5 is a side view of the crossbow case of FIG. 1.

FIG. 6 is an end view of the crossbow case of FIG. 1; and, FIG. 7 is an end view of the crossbow case of FIG. 1.

The broken line showing of unclaimed subject matter is included for the purpose of illustrating environment and forms no part of the claimed design.
